(57) **CLAIM**

We claim, the ornamental design for a light fixture, as shown and described.

DESCRIPTION

FIG. 1 is a first perspective view of the light fixture of the invention;

FIG. 2 is a second perspective view thereof;

FIG. 3 is a top plan view thereof;

FIG. 4 is a side elevation view thereof, with the opposite side being a mirror image thereof;

FIG. 5 is a front elevation view thereof; and,

FIG. 6 is a rear elevation view thereof.

The degree of transparency or opaqueness of the lens of the light fixture forms no part of the claimed design.

The phantom lines shown in FIG. 1-4 and FIG. 6 are environmental and not part of the claimed design.

References to "side", "top", "front" and "rear" in the figure descriptions are not meant to require certain in-use orientation, a light fixture according to the claimed design may be used in any orientation.
